CLAIM

The ornamental design for a side walls for a container, as shown and described.

DESCRIPTION

FIG. 1 is a side elevation illustrating a side wall profile design for a container in accordance with a first embodiment of my new design;

FIG. 2 is a top plan view thereof;

FIG. 3 is a bottom plan view thereof;

FIG. 4 is a side elevation illustrating a side wall profile design for a container in accordance with a second exemplary embodiment of my design;

FIG. 5 is a top plan view thereof;

FIG. 6 is a bottom plan view thereof;

FIG. 7 is a side elevation illustrating a side wall profile design for a container in accordance with a third exemplary embodiment of the invention;

FIG. 8 is a top plan view thereof;

FIG. 9 is a bottom plan view thereof;

FIG. 10 is a side elevation illustrating a side wall profile design for a container in accordance with a fourth exemplary embodiment of the invention;

FIG. 11 is a top plan view thereof;

FIG. 12 is a bottom plan view thereof;

FIG. 13 is a side elevation illustrating a side wall profile design for a container in accordance with a fifth exemplary embodiment of the invention;

FIG. 14 is a top plan view thereof;

FIG. 15 is a bottom plan view thereof;

FIG. 16 is a side elevation illustrating a side wall profile design for a container in accordance with a sixth exemplary embodiment of the invention;

FIG. 17 is a top plan view thereof;

FIG. 18 is a bottom plan view thereof;

FIG. 19 is a side elevation illustrating a side wall profile design for a container, partially textured, in accordance with a seventh exemplary embodiment of the invention;

FIG. 20 is a top plan view thereof; and,

FIG. 21 is a bottom plan view thereof.

The dotted line top and bottom configurations are intended to illustrate environment only, and do not form any part of the claimed subject matter.

The front and rear elevations of each embodiment are the same in appearance as the side elevations.
